UNITED STATES PATENT OFFICE.

JOSEPH M. SPENCER, OF PHILADELPHIA, PENNSYLVANIA, ASSIGNOR OF ONE-THIRD
TO JOSEPH GENSLER, OF PHILADELPHIA, PENNSYLVANIA.

DRYING-MACHINE.

1,097,144.

Specification of Letters Patent.

Patented May 19, 1914.

Application filed May 1, 1912. Serial No. 694,398.

To all whom it may concern:

Be it known that I, JOSEPH M. SPENCER, a citizen of the United States, residing at Philadelphia, in the county of Philadelphia and State of Pennsylvania, have invented new and useful Improvements in Drying-Machines, of which the following is a specification.

The invention relates to drying machines and has for an object to provide a machine for drying and carbonizing materials, such as cloth and the like.

My invention embodies among other features a casing provided with means for feeding the cloth onto a series of rollers revolvably mounted within the casing and heated, the said rollers being arranged in tiers so that the cloth will pass from one tier to another, during which process the cloth becomes properly dried, conveying means being provided for then removing the cloth from the casing and conveying the same to a desired place, suitable air blowing means being provided for forcing currents of air into the casing, beneath the rollers, to prevent the cloth from becoming burned or singed the mentioned rollers being adapted to receive steam or hot air, which passes into the rollers at one end thereof and is exhausted at the other end thereof.

Reference is to be had to the accompanying drawings, constituting a part of this specification, in which similar characters of reference denote corresponding parts in all the views, and in which—

Figure 1 is a side elevation of my device, one of the sides thereof having been removed to disclose the underlying structure. Fig. 2 is a vertical longitudinal sectional view. Fig. 3 is a horizontal sectional view taken on the line 3—3 in Fig. 1, looking toward the rollers. Fig. 4 is a vertical transverse sectional view taken on the line 4—4 in Fig. 1, looking in the direction of the arrow. Fig. 5 is a vertical sectional view taken on the line 5—5 in Fig. 1, looking in the direction of the arrow. Fig. 6 is an enlarged vertical sectional view taken through one of the rollers showing the manner of mounting the

same and the safety valve thereon. Fig. 7 is 50 an enlarged fragmentary sectional view of one of the air nozzles.

Referring more particularly to the views, I provide a casing 10 provided at the front end and near the top with a transversely extending slot 11 and at the rear end and near the bottom with a transversely extending slot 12. The casing 10 at the front thereof is provided with a forwardly extending platform 13 and journaled on the platform are 60 shafts 14, having rollers 15 keyed thereto, an endless conveyer 16 being mounted to operate over the rollers 15 and arranged horizontally. A plurality of shafts 18 is journaled in the casing 10, rollers 19 being keyed to the 65 said shafts and being revoluble therewith and mounted on the said rollers is a spiked endless apron 20, the outwardly extending spikes on the said apron being arranged to extend upwardly when portions of the apron 70 are exposed on the front side of the casing 10, suitable sprocket wheels and chains being secured to one of the shafts 14 and one of the shafts 18 and connected with suitable driving mechanism for operating both the conveyer 16 and the apron 20, one of the shafts 18 being mounted adjacent the slot 11 in the casing for a purpose that will be hereinafter 75 more fully disclosed.

Journaled in sides 21 of the casing 10 are 80 rollers 22, the said rollers being arranged in horizontal tiers 23 with the last roller in the second tier mounted to extend a distance beyond the last roller in the first tier and the first roller in the third tier mounted to extend a distance in front of the first roller in the second tier, the first roller in the first tier being mounted immediately below and adjacent the slot in the casing 10.

Each of the rollers 22 consists of a tubular body 24 terminating in tubular shanks 25, which are journaled in the sides 21 of the casing 10, the ends of the said shanks being adapted to project outwardly beyond the sides of the casing. Keyed to one of the shanks 25 of each of the rollers 22 is a toothed wheel 26 engaging a worm 27, keyed to a horizontally extending shaft 28, it

being understood that the shaft 28 is journaled exteriorly of the casing 10, the said shaft being provided with a worm 27 for each wheel 26 and each of the said rollers 5 being provided with a wheel 26 said wheels being also mounted exteriorly of the casing 10. Thus when the shaft 28 is rotated the rollers in each tier will revolve in the same direction, a shaft 28 being provided for each 10 tier of rollers. The front ends of the shafts 28 are journaled in suitable bearings 29 secured to the casing 10 and the rear end of the first shaft 28, for the first tier of rollers, has secured thereto a beveled wheel 30 in 15 mesh with a beveled wheel 31 secured to an intermediate shaft 32 and having a beveled wheel 33 keyed to the lower end thereof, the second shaft 28 being provided at the rear end with a beveled wheel 34 in mesh 20 with the beveled wheel 35 keyed to an intermediate shaft 36 having a beveled wheel 37 keyed to the lower end thereof and in mesh with a beveled wheel 38, keyed to the rear end of the third or lowermost shaft 28, 25 the intermediate shafts 32 and 36 being revolvably mounted on the casing in any suitable manner. Thus, it will be seen that the first shaft 28 will operate in one direction, the second shaft 28 will operate in the reverse direction and the third shaft 28 will operate in a direction reverse to the second shaft or in the same direction as the first shaft. In this manner the first tier of rollers will conveniently rotate toward the right, 30 the second tier of rollers will rotate toward the left and the third tier of rollers will rotate toward the right, for a purpose that will be hereinafter more fully disclosed. The last or third shaft 28 has keyed thereto a 35 suitable pulley 39, adapted to receive a belt 40 extending downwardly through the casing 10 for connection with a suitable driving mechanism, thus providing a means for imparting rotation to the shafts 28 and consequently to the rollers 22 so that the shafts and rollers will operate in the direction mentioned heretofore.

Rigidly mounted on one of the outer sides 21 of the casing 10 by means of suitable brackets 41 is a pipe 42, having connection with a suitable steam supply pipe 43, connected to one end of the pipe 42 and secured to the pipe 42, at points opposite to each of the rollers 22 are auxiliary steam 45 pipes 44, each having a head 45 connected thereto, the said heads being adapted to overlap the extended portions of one of the shanks 25 of each of the rollers 22, suitable packings 46 being mounted within the heads 50 and engaging the mentioned shanks 25 so that the steam in the pipe 42 can pass into the rollers 22 while the same are revolving. In a similar manner an exhaust pipe 47 is rigidly mounted by means of suitable brackets

48, on the other side 21 of the casing 10 and the extended portions of the other shanks 25 of the rollers 22 extend within the exhaust pipe 47, suitable packings 49 being interposed between the overlapping edges of the exhaust pipe 47 and the extended portions of the shanks 25, to permit the steam in the rollers 22 to pass outwardly into the exhaust pipe 47, without in any manner hindering the revolutions of the rollers. The extended portions of the shanks 25, extending within the exhaust pipe 47, are each provided with a cap 50 bolted on or formed with the shank and having perforations 51 therein. Mounted on the cap is a valve 52 having a shank 53, encircled by a spring 54, the said shanks 53 being provided with heads 55, with one end of each of the springs 54 abutting against the head 55 on each shank and the cap 50 on each of the extended portions of the shanks 25, the said springs 54 being under tension so that the steam admitted into each of the rollers 22 will be prevented from passing outwardly into the exhaust pipe 47 until the steam attains sufficient pressure to move the valve 52 away from the cap 50, thus permitting the excess steam to pass through the perforations 51 and into the exhaust pipe 47. As mentioned, each of the rollers 22 is provided with means for admitting steam thereto and permitting the steam to escape therefrom, so that each roller will at all times have substantially the same amount of steam therein, the steam in each roller being of substantially the same pressure, due to the fact that each of the 100 rollers is provided with a valve 52 operable as described.

Mounted exteriorly of the casing 10 is a suitable blower 56, of any desired construction or make, the said blower being connected with a suitable driving mechanism and connected to the blower and extending upwardly to one side of the rear end of the casing is a main air pipe 57, auxiliary air pipes 58 being extended from the main pipe 57 at various intervals and extending into the casing 10, the inner termini of the respective auxiliary air pipes 58 being beneath the horizontal plane of the adjacent tiers of rollers 22. Mounted on the inner ends of the auxiliary air pipes 58 are air nozzles 59, the said air nozzles being preferably elongated in shape and of a width substantially equal to the width of the casing 10. The air nozzles 59, secured to the inner ends of the auxiliary air pipes 58, will be arranged adjacent the rear ends of the tiers of rollers 22 and between the same so that currents of air from the blower 56, passing through the main pipe 57 and the auxiliary air pipes 58, will be forced outwardly through the nozzles 59 and passed horizontally beneath the tiers of rollers 22, the currents of air being then

carried upwardly by the heat from the rollers. As a guard against any foreign matter passing through the nozzles 59 and contacting with the cloth which is being dried in the casing, screens 60 are mounted on the nozzles 59 to cover the openings thereof, the said screens being of a fine mesh so that any foreign matter will be prevented from passing onto the cloth. An exhaust air flue 61 is secured to the top of the casing 10 and opens into the casing, the said air flue being adapted to carry away the air after the same has been forced outwardly from the nozzles 59 and heated by the heat from the rollers 22, a damper 62 being mounted within the exhaust flue 61 and operable to regulate the amount of heated air to be carried from the casing, the upper end of the said flue 61 being adapted to extend to the atmosphere or into some receptacle into which the heated air can be harmlessly exhausted.

Journaled within the casing 10, immediately beneath the last roller 22, in the last tier of rollers, is a shaft 63 having a roller 64 keyed thereto and mounted to extend around the roller 64 is an endless conveyer 65, extending outwardly through the slot 12 in the casing 10, a suitable sprocket wheel 63' being keyed to the shaft 63, exteriorly of the casing 10 and connected by means of a chain 63'' with one of the wheels 26 as shown in Fig. 1, thus operating the endless conveyer.

In the use of my device, the cloth, which is to be dried and which usually comes in long rolls, is fed onto the conveyer 16 at the front end of the casing 10. As the cloth moves along the conveyer 16 the end of the cloth will be gripped by the spikes on the apron 20 thus drawing the cloth upwardly through the slot 11, after which the end of the cloth will fall onto the first roller 22 of the first tier of rollers. Now as the rollers 22, in the first tier of rollers are revolved toward the right, the cloth will be fed from one roller to the other and will move toward the right end of the casing. When the end of the cloth reaches the end of the first tier of rollers, the cloth will gravitationally fall onto the last roller in the second tier of rollers and the rollers of the second-mentioned tier, revolving toward the left or front of the casing, will move the cloth toward the front of the casing. Therefore, when the end of the cloth passes from the first roller in the second tier of rollers, the mentioned end will gravitationally fall onto the first roller in the third tier of rollers. As mentioned heretofore the rollers of the third tier of rollers revolve toward the right in the same direction as the rollers of the first tier so that the cloth will be fed toward the right or rear end of the casing, after which it will fall onto the con-

veyer 65, which will convey the cloth out of the casing 10 and to the packing room or any other desired place where the cloth should be conveyed after it has been properly dried.

By forcing air outwardly from the nozzles 59, by means of the blower 56, the mentioned air will be received between the tiers of rollers as has been mentioned and will rise upwardly and absorb the heat which is radiated from the roller, it being understood that steam is admitted to each of the rollers 22 through the medium of the steam supply pipe 42 and exhausted from the rollers through the exhaust pipe 47, as mentioned heretofore. Now, as the cloth passes over the rollers, if the heat from the rollers were too intense, the cloth would be singed or burned and in order to obviate this, currents of air are forced outwardly from the nozzles 59 as mentioned, and the mentioned currents of air absorbing the superfluous heat will pass upwardly and out of the air flue 61, the exit of the air through the air flue 61 being regulated by the damper 62.

It will be readily understood that when the cloth is fed over the rollers, the action of the heat on the cloth will not only dry the same, but by regulating the intensity of the heat by means of the amount of steam within the rollers and the amount of heated air that is permitted to pass outwardly from the casing 10, the heat within the casing can be retained at a degree of intensity, which will act as a carbonizing agent for the cloth, to give the cloth a rich, smooth outer appearance, while at the same time the heat will tend to set the dye with which the cloth may be impregnated.

From the foregoing description, it will be readily seen that a large amount of cloth can be easily and quickly passed through the casing 10, in the manner described and for the purposes mentioned, the amount of heat produced within the casing being controllable at all times and the amount of steam admitted to the rollers being substantially of equal intensity in each roller, thus preventing the cloth from suddenly coming in contact with a roller having a greater amount of heat than the preceding rollers, which act would in all probability burn or singe the cloth so that the same would not be fit for commercial purposes.

It will be understood that various departures may be made from the particular construction of my device, as disclosed in the drawings, without departing from the spirit of the invention, and that the scope of the invention is defined in the appended claim.

I claim:—

A drying machine comprising a casing, tubular rollers revolvably mounted within the said casing, a steam supply pipe mounted

exteriorly of the said casing and having connection with the said roller at one end to admit steam therein, exhaust pipe having connection with the other ends of said rollers for exhausting the steam therefrom and valves mounted in the said last named ends of the said rollers at the centers thereof for regulating the pressure at which steam is

exhausted from the rollers into the said exhaust pipe. 10

In testimony whereof I affix my signature in presence of two witnesses.

JOSEPH M. SPENCER.
